Patented Aug. 3, 1976

240,863

MICROFILM READER-PRINTER

Richard J. Olson, Pittsford, N.Y., assignor to Eastman
Kodak Company, Rochester, N.Y.

Continuation-in-part of design application Ser. No.
379,148, July 13, 1973. This application Feb. 3,
1975, Ser. No. 546,565

Term of patent 14 years

Int. Cl. D16—05

U.S. Cl. D16—28

FIG. I

FIG. 2

FIG. 3

FIG. 4

FIG. 1 is a left front perspective view of a microfilm reader-printer showing my new design;

FIG. 2 is a right side elevational view thereof;

FIG. 3 is a rear elevational view thereof; and

FIG. 4 is a bottom plan view thereof.

This is a continuation-in-part of design application Ser. No. 379,148, filed July 13, 1973.

I claim:

The ornamental design for a microfilm reader-printer, substantially as shown.
